UNITED STATES PATENT OFFICE.

JOHN B. FREYSINGER, OF NEW BRITAIN, CONNECTICUT, ASSIGNOR TO KRISCHER'S MANUFACTURING COMPANY, OF BROOKLYN, NEW YORK, A CORPORATION OF NEW YORK.

BELT BUCKLE.

Application filed December 28, 1926. Serial No 157,435.

This invention relates to a belt buckle which may be either of the so-called "trench" type or one provided with a tongue which passes through holes in the belt to secure it in position. More particularly, the invention is concerned with a buckle of either style having means by which it may be readily secured on one end of the belt, this means forming an integral part of the buckle and being arranged so that the attachment of the buckle to the belt is a simple operation with the attaching means also serving to center the end of the belt with reference to the buckle while it is being attached.

In belts heretofore used it has been customary to attach one end of the belt to the buckle by passing its end around the center bar and then securing it to the remainder of the belt in any convenient manner, as by means of a row of stitching, or the like. Where the belt has a tongue which is passed through openings in the belt to adjust the latter and hold it taut, the end of the belt to be attached to the buckle is formed with an opening through which the tongue may pass and the end is then turned around the bar as before and is secured to the rest of the belt in the usual manner. Attaching the buckle to the belt in this way involves a considerable amount of labor and unless the operations are carried on with care, loss may result due to faulty stitching which makes the belt unsuitable for the market.

The object of the present invention is to provide a buckle having means by which it may be attached to one end of the belt with great facility so that this operation involves only small labor charges. This new attaching means does not add materially to the cost of the buckle, and it further provides a guide or centering device which insures the proper adjustment of the belt to the buckle. This attaching means is supported in place so as to be wholly concealed from view when the buckle is in use and it is so mounted on the buckle that it requires no changes in those parts of the frame that are visible when the belt is in use. Accordingly, a buckle with the improved attaching means may be of any desired shape or form and may be used satisfactorily with belts of different thicknesses and widths.

In the preferred form of embodiment of the invention, the buckle includes a frame defining a central opening and a center bar sub-

dividing this opening to provide apertures for the free end of the belt. A gripping member or ratchet bar is mounted on the rear face of the center bar and cooperates with the bar to provide means for gripping an end of the belt tightly. This ratchet bar carries pins which extend through ears struck from the center bar near the ends thereof and lying spaced inwardly from the edges of the frame. The ratchet bar is thus mounted in position wholly independently of the frame and its use requires no alterations in the frame construction. In addition, the ears which are spaced apart substantially the width of the belt, serve to guide the end of the latter during the attaching operation and this insures that the buckle will be properly attached to the belt by the workman so that the belt is in saleable condition when it is completed.

For a better understanding of the invention, reference may be had to the accompanying drawings, in which

Fig. 1 is a face view of the buckle showing it attached to the belt and in use.

Fig. 2 is a sectional view on the line 2—2 of Fig. 1.

Fig. 3 is an enlarged face view showing the buckle attached to the belt.

Fig. 4 is a rear view corresponding to Fig. 3.

Fig. 5 is a sectional view on the line 5—5 of Fig. 3.

Fig. 6 is a face view of a buckle having a tongue.

Fig. 7 is a sectional view on the line 7—7 of Fig. 6, and Fig. 8 is a perspective view of the clamping bar.

Referring now to the drawings, one form of buckle of the present invention is illustrated at 10 in Fig. 1. This buckle is of the trench type, the free end of the belt being held in adjusted position with reference to the buckle by the friction of the belt against portions of the buckle. The buckle may be made of different metals and is preferably of sheet metal stamped or otherwise formed to the desired shape. The buckle illustrated is of general rectangular shape having side bars 11 at opposite sides of the belt and end bars 12 extending across the belt. These bars have a substantial width in the type of buckle illustrated but the buckle may have varying outlines or shapes as may be desired, and the shape of the frame will depend on the outline.

The side and end bars 11 and 12 define a central opening 13 which is sub-divided by a center bar 14 to provide two smaller openings 15 and 16. At the outer edge of each smaller opening, the metal of the buckle is bent rearwardly to form a flange 17 and when the belt is in use, the free end of the belt strap 18 is led behind one edge of the buckle around one flange 17 forwardly through opening 16, over the center bar 14 and rearwardly through opening 15, the free end also passing over the second flange 17 at the edge of the opening 15. With this arrangement, the free end of the belt is held against movement by its engagement by the flanges and center bar and will be held sufficiently secure for all general purposes.

In order to attach the end 19 of the belt to the buckle there is used a ratchet bar 20 which is illustrated by Fig. 8. This bar has a flat portion 21 by which it may be manipulated and another portion 22 extending at an angle to the flat portion, this extension having serrations 23 in one edge. To mount the ratchet bar in position, ears 24 are struck from the center bar 14 at both ends thereof adjacent the points where the ends of the bar merge with the side frame members. These ears extend rearwardly substantially at right angles to the plane of the center bar and are punched to receive pins 25, one at each end of the ratchet bar. The ratchet bar is of the usual construction and it is so arranged that it may be swung by the handle portion 21 to a position in which the end 19 of the belt may be placed between the rear face of the center bar 14 and the ratchet bar; then the ratchet bar is moved to the position illustrated in Fig. 7 where the teeth on the edge of the ratchet bar bear against the end of the belt so that this end is held firmly between the row of teeth and the rear face of the center bar.

It will be seen that with the ratchet bar mounted in this manner, and supported independently of the side bars of the frame, the openings 15 and 16 through the frame for the passage of the belt may be of less width than the buckle and the buckle may have frame members with large visible surfaces wholly enclosing the central opening. At the same time, the ratchet bar employed has a length not substantially greater than the width of the belt and the supporting ears in which the end of the belt is held act as guides as the edges of the belt to center it with reference to the buckle. The ratchet bar thus provides a convenient means for securing the buckle to the belt and in the new buckle this ratchet bar is concealed from view. Preferably, the center bar is formed with an indented portion 26 along one edge so that the edge 27 of the ratchet bar may slightly project so that it may be freely grasped for manipulation. However, the main part of the ratchet bar lies behind the center bar, and is hidden by the

latter when the belt is not in use, and when the belt is being worn, the strap overlies the center bar and thus no parts of the center bar or ratchet bar are visible.

The novel buckle can be made in either the trench form above described or may have a tongue to hold the belt in adjusted position. This latter type is shown in Fig. 6 and here the center bar 14 has an ear 24 struck from it at both ends to provide a support for the ratchet bar and also has an opening 28 formed midway of its ends and near one side for holding a tongue 29. This tongue may be a piece of wire with a loop 30 at one end passing through the opening 28 with the free end 31 of the tongue overlying one end member 12 of the frame. The ratchet bar in this type of buckle is again supported between ears which serve as guiding means for the end of the belt which is to be attached to the buckle during this attaching operation. The ratchet bar has a gripping portion 22 cooperating with the bar 14 to grip the end of the belt and an operating portion 21 which, when the ratchet bar is in gripping position, lies close to the rear face of the bar 14 at one edge thereof, the operating portion overlying the opening in which the tongue is mounted and having a recess 21' shown in Figs. 7 and 8, to receive the looped end 30 of the tongue. With this arrangement, the ratchet bar is wholly concealed behind the frame bar 14 and although the frame bar may be made quite narrow, the ratchet bar does not interfere with the free manipulation of the tongue.

The new buckle may be made in any shape and size desired and since the ratchet bar is mounted in place quite independently of the frame members, the use of the ratchet bar places no limit on the outlines that the frame may have. The formation of the ears which support the ratchet bar by striking these ears from the center bar does not weaken the buckle and by this method of forming a support for the ratchet bar, the ears are positioned so that they support the ratchet bar and also simplify the attaching operation. The use of the ratchet bar mounted in this way on the buckle does not increase the cost of the buckle to any substantial extent and further effects considerable savings in the final cost of the belt because the attachment of the new buckle to the belt is a simple operation, consuming little time and thus involving small labor charges per belt. Also the new attachment means insures that each belt and buckle will be properly secured together, and ready for the market and as the securing means is attached to the buckle in a way that results in no alteration in the outline of or appearance of the frame, the frame may be of any shape or size desired.

I claim:

1. A belt buckle comprising a frame hav.

ing an opening subdivided by a bar, a tongue mounted on the said frame bar and adapted to extend across the opening with one end overlying the frame at one side of the opening, a pair of ears extending from the rear face of the frame bar and lying inwardly from the outer edges of the frame, and a gripping bar mounted in the ears and cooperating with the frame bar to grip the end of the belt, this gripping bar having an operating portion extending toward one edge of the frame bar when the gripping bar is in effective position, the said portion overlying the point of attachment of the tongue to the frame bar but lying within the outer lines of the frame bar.

2. A belt buckle comprising a frame having a central opening subdivided by a bar,

a tongue mounted in an opening in the said frame bar centrally and adjacent one edge thereof, this tongue being adapted to extend across the opening with one end overlying the frame at one side of the opening, a pair of ears extending from the rear face of the bar and lying inwardly from the outer edges of the frame, and a gripping bar mounted in the ears and having a portion adapted to cooperate with the frame bar to grip the end of the belt and an operating portion extending toward one edge of the frame bar when the gripping bar is in effective position, this operating portion having a slot within which a portion of the tongue is received.

In testimony whereof I affix my signature.

JOHN B. FREYSINGER.
